UNITED STATES PATENT OFFICE.

ALBERT E. MATT, OF STILLWELL, INDIANA.

BOTTLE-STOPPER.

1,153,240.

Specification of Letters Patent. Patented Sept. 14, 1915.

Application filed October 17, 1914. Serial No. 867,179.

To all whom it may concern:

Be it known that I, ALBERT E. MATT, a citizen of the United States, residing at Stillwell, in the county of Laporte and State of Indiana, have invented certain new and useful Improvements in Bottle-Stoppers, of which the following is a specification, reference being had to the accompanying drawings.

10 This invention relates to improvements in bottle stoppers, and particularly to a stopper which is adapted to indicate that the bottle in which the stopper is mounted contains poison.

15 An object of this invention is the provision of a stopper in which means is provided so that the user of the bottle will be advised either by touch or sight, that the bottle contains poison.

20 A further object of this invention is the provision of a stopper from which a sharpened pin projects, so that a person handling the bottle in the dark will be warned as to its contents, means being provided to prevent 25 removal of the pin while the stopper is mounted in the bottle, the pin being readily removable from the stopper when the same is disengaged from the bottle.

With these and other objects in view, my 30 invention consists in the novel construction, combination, and arrangement of parts, to be hereinafter more fully described, claimed, and illustrated in the accompanying drawings, in which—

35 Figure 1 is an elevational view of the neck of a bottle showing my improved stopper mounted therein; Fig. 2 is a sectional view on the line 2—2 of Fig. 1; and Fig. 3 is an outer end view of the stopper.

40 Referring more particularly to the drawing, the numeral 1 designates a bottle which may be of any desired construction, and which is provided with the usual neck 2, my improved stopper 3 which is constructed of 45 cork, rubber, or any other suitable material being mounted in the usual manner in the neck. Fastened to the stopper at its outer end is a cap 4 which is preferably constructed of white porcelain, the cap being of relatively greater diameter than the stopper, whereby the cap engages the extremity of the neck of the bottle to prevent the stopper from being forced entirely into the bottle, and providing means whereby the stopper 55 may be readily removed from the bottle. The outer face of the cap 4 has printed or

otherwise affixed thereon, the usual skull and cross bones and the word poison which is preferably red in color, so that a person about to use the bottle will readily see that 60 the same contains poison.

Extending centrally from the cap is a sleeve 4', the sleeve being embedded in the stopper, and extends substantially half its length. A pin 5 is adapted for engagement 65 through the axial center of the stopper and through the sleeve 4' and the cap 4, the outer or pointed end 6 of which projects outwardly of the cap 4 through the central opening therein, and the inner end of the 70 pin being provided with a head 8 which is engaged against the inner end of the stopper. The head 8 is preferably formed of porcelain or the like and covers the entire inner face of the stopper to protect the same 75 from acids which may be contained within the bottle. The pin 5 frictionally engages the inner wall of the sleeve 4', whereby the pin is prevented from dropping into the 80 bottle, and to prevent accidental loss of the stopper a flexible wire 9 is secured at one end around the neck 2 of the bottle, the other end of the wire being secured around the stopper under the cap 4. The wire 9 is of a suitable length to allow the stopper to be 85 entirely removed from the neck, the wire serving to retain the stopper in connection with the bottle.

It will be readily understood that if a person accidentally grasps a bottle containing 90 my improved stopper from among a group of bottles while in the dark, he will be reminded as to the contents of the bottle as the pointed end 6 of the pin will prick the fingers as the person attempts to remove the 95 stopper from the bottle. The cap 4 having the printed matter thereon together with the upstanding pin 5 clearly indicates the character of the bottle during the day time, and a person aware of the presence of the 100 pin 5 may easily disengage the stopper from the bottle without pricking the fingers.

While I have illustrated the stopper as used in connection with a bottle, it will be readily understood that the same may be 105 used in connection with a can, tube, or any other receptacle containing a poisonous substance.

Having thus fully described my invention, what I desire to claim and secure by Letters 110 Patent is:—

1. A stopper for bottles or the like having

a cap secured to its outer end, said cap having a central laterally projecting sleeve embedded within the stopper, a pin disposed through the stopper from its inner end, said pin being frictionally engaged within said sleeve, the pin projecting at its outer end through said cap and being pointed, and the opposite end of the pin having a head formed thereon for engagement against the inner end of the stopper.

10 2. The combination with a bottle neck, of a stopper including a cylindrical body member insertible in the neck, said body member being provided with a vertically extending bore which opens through its upper end, a cap member mounted on the upper end of

the body member, a sleeve depending from the lower face of the cap and extending into the bore of the body member, said sleeve being freely seated in the bore, a pin extending through the body member and through the sleeve and cap, the upper end of said pin projecting a considerable distance above the cap member, and a head carried by the inner end of the pin and bearing against the inner end of the cap member.

15 In testimony whereof I hereunto affix my signature in the presence of two witnesses.

ALBERT E. MATT.
